PHYSIOLOGICAL UNIT FOR MONITORING BODY FUNCTIONS

Raymond Ugo Cappelli, Hillsboro, and Jack Randolph Nelson, Beaverton, Oreg., assignors to Tektronix, Inc., Beaverton, Oreg., a corporation of Oregon

Filed Mar. 20, 1967, Ser. No. 6,283

Term of patent 14 years

(Cl. D83—1)

FIG. 1

FIG. 2

FIG. 3

FIG. 4

FIG. 5

FIG. 6

FIG. 1 is a front elevation of a physiological unit for monitoring body functions, showing our new design; FIG. 2 is a top plan view thereof; FIG. 3 is an elevation as seen from the right of FIG. 1; FIG. 4 is a bottom plan view of the unit; FIG. 5 is a rear elevation of the unit; and FIG. 6 is a side elevation as seen from the left of FIG. 1.

The dominant features of my design reside in the portions shown in full lines.

I claim:

The ornamental design for a physiological unit for monitoring body functions, as shown and described.
